Primary Examiner — Darlington Ly

(57) **CLAIM**

The ornamental design for a motorcycle, as shown and described.

DESCRIPTION

The patent or application file contains at least one drawing executed in color. Copies of this patent or patent application publication with color drawing(s) will be provided by the Office upon request and payment of the necessary fee.

1. Motorcycle

1.1 is a left side elevation view of a motorcycle embodying our new design;

1.2 is a right side elevation view thereof;

1.3 is a rear elevation view thereof;

1.4 is a front elevation view thereof;

1.5 is a top, front, and left side perspective view thereof;

1.6 is a top, front, and right side perspective view thereof;

1.7 is a top, rear, and left side perspective view thereof;

1.8 is a top, rear, and right side perspective view thereof;

1.9 is a top plan view thereof; and

1.10 is a bottom plan view thereof.

1 Claim, 10 Drawing Sheets
